UNITED STATES PATENT OFFICE

161,158

SHADOW BOX

John A. Bu Gay, Chicago, Ill., assignor to Quality
Molding Co., Chicago, Ill., a partnership

Application February 28, 1950, Serial No. 8,201

Term of patent 3½ years

(Cl. D33—3)

To all whom it may concern:

Be it known that I, John A. Bu Gay, a citizen of the United States of America, residing at Chicago, in the county of Cook and State of Illinois, have invented a new, original, and ornamental Design for Shadow Box, of which the following is a specification, reference being had to the accompanying drawing, forming a part thereof.

Fig. 2 is a side view of the same.

I claim:

The ornamental design for a shadow box, as shown.

JOHN A. BU GAY.
